United States Patent Office.

D. D. MALLORY, OF BALTIMORE, MARYLAND.

Design No. 3,102, dated July 14, 1868.

DESIGN FOR A TRADE-MARK.

The Schedule referred to in these Letters Patent and making part of the same.

TO ALL WHOM IT MAY CONCERN:

Be it known that I, D. D. MALLORY, of the city and county of Baltimore, and State of Maryland, have invented a new Design for Trade-Mark for Oyster-Cans, of which the following is a full, clear, and exact description, reference being had to the accompanying drawings, making part of this specification.

My invention is represented by a side view of a metallic can, upon which the design is shown.

This design consists in a diamond-shaped depression, *a*, stamped into the side of a sheet-metal can, *A*, and having a circle or ring, *r*, inscribed or stamped within it. The name of the firm, "D. D. Mallory & Co.," is arranged within the circle, around the upper half thereof, as seen in the drawing. Directly under the centre of the name is a dash, *d*, below which is the word "Packers," the words "D. D. Mallory & Co." and "Packers" being arranged so as to form a semicircle. Under the word "Packers" is the word "Baltimore," and beneath this is the abbreviation "Md."

What I claim as my invention, and desire to secure by Letters Patent, is—

The design for a trade-mark for an oyster-can, herein set forth and shown.

To the above specification of my design I have signed my hand, this 21st day of May, 1868.

D. D. MALLORY.
